COMBINED WIND WING AND HINGES

Paul Bernhardt, North Long Beach, and Dorothy Deen,
Inglewood, Calif.

Application December 5, 1952, Serial No. 22,578

Term of patent 14 years

(Cl. D14—6)

To all whom it may concern:

Be it known that we, Paul Bernhardt and Dorothy Deen, citizens of the United States, residing in North Long Beach and Inglewood, respectively, in the county of Los Angeles, State of California, have invented a new, original, and ornamental Design for a Combined Wind Wing and Hinges, of which the following is a specification, reference being had to the accompanying drawing forming part thereof.

Figure 1 is a front perspective view of a combined wind wing and hinges embodying our new design.

Figure 2 is a rear view thereof.

Figure 3 is an edge view taken as from a position 3, relative to Figure 2.

Figure 4 is an edge view taken from a position 4 of Figure 2.

Figure 5 is a top view thereof.

Figure 6 is a bottom view thereof.

The characteristic features of applicants' design reside particularly in the configuration of the hinges and their relation to the edge of the wind wing.

We claim:

The ornamental design for a combined wind wing and hinges, substantially as shown.
